(57) **CLAIM**

The ornamental design for a spray dispensing container, as shown and described.

DESCRIPTION

FIG. 1 is a bottom, front perspective view of a spray dispensing container showing my new design in a closed configuration;

FIG. 2 is a top, rear perspective view thereof;

FIG. 3 is a front view thereof;

FIG. 4 is a rear view thereof;

FIG. 5 is a side view thereof;

FIG. 6 is a side view thereof wherein the container is rotated along a horizontal axis 180° in relation to the view illustrated in FIG. 5;

FIG. 7 is a top plan view thereof;

FIG. 8 is a bottom plan view thereof; and,

FIG. 9 is a bottom, front perspective view showing my design in an open configuration.
